(57) **CLAIM**

The ornamental design for a split-screen display device, as shown and described.

DESCRIPTION

FIG. 1 is a front perspective view of a split-screen display device, showing my new design;

FIG. 2 is a rear perspective view thereof;

FIG. 3 is a front view thereof;

FIG. 4 is a rear view thereof;

FIG. 5 is an enlarged left-side view thereof;

FIG. 6 is an enlarged right-side view thereof;

FIG. 7 is a top view thereof;

FIG. 8 is a bottom view thereof;

FIG. 9 is an enlarged detail view of area 9 in FIG. 1 thereof;

FIG. 10 is an enlarged detail view of area 10 in FIG. 1 thereof;

FIG. 11 is an enlarged detail view of area 11 in FIG. 1 thereof;

FIG. 12 is an enlarged detail view of area 12 in FIG. 2 thereof;

FIG. 13 is an enlarged detail view of area 13 in FIG. 3 thereof;

FIG. 14 is an enlarged detail view of area 14 in FIG. 3 thereof;

FIG. 15 is an enlarged detail view of area 15 in FIG. 4; and,

FIG. 16 is an enlarged detail view of area 16 in FIG. 5.

The even-dash broken lines in the drawings illustrate portions of the split screen display device, which form no part of the claimed design.

The dot-dot-dash broken lines represent the extents of the detail views and form no part of the claim thereof.

(Continued)

The irregular-dash broken lines, showing a logo on the front of the split-screen display device, form no part of the claimed design.

1 Claim, 16 Drawing Sheets
